UNITED STATES PATENT OFFICE.

JOHN NEVILLE, OF JERSEY CITY, NEW JERSEY.

FURNACE.

SPECIFICATION forming part of Letters Patent No. 321,519, dated July 7, 1885.

Application filed March 12, 1884. (No model.)

To all whom it may concern:

Be it known that I, JOHN NEVILLE, of Jersey City, in the county of Hudson and State of New Jersey, have invented a certain new and useful Improvement in Furnaces, of which the following is a specification.

My invention relates to a combined furnace having smelting and roasting chambers, the heat and products of combustion of the smelting-chamber being utilized for heating the roasting-chamber.

My invention consists in a horizontal furnace comprising a smelting-chamber accessible through doors at the side and outer end and a roasting-chamber at right angles thereto, accessible through doors at the sides, as hereinafter described, and pointed out in the claims.

In the accompanying drawings, Figure 1 is a plan view of my improved furnace, partly in a horizontal section on the line 1 1, Fig. 3. Fig. 2 is a vertical section on the line 2 2, Fig. 1. Fig. 3 is a vertical section on the line 3 3, Fig. 1.

My furnace has a smelting-chamber, A, and a roasting-chamber B at right angles thereto. These chambers are connected by a flue, C, so that the products of combustion and heat pass from the smelting-chamber A to the chimney D through the roasting-chamber B as their only outlet. The direction of the heat and products of combustion is indicated by the arrows.

The smelting-chamber A, I prefer to heat as follows: N is the fire-chamber, having between it and the smelting-chamber a bridge-wall, O, formed with a hollow hot-air chamber, J, communicating with the chamber A by means of pipes I and passages L, as shown

in Figs. 1 and 2, air being admitted into the bridge-wall chamber through a pipe, M. Access is had to the floor of the smelting-chamber through doors P P' at the side and outer end, respectively.

Above the floor of the roasting-chamber is a horizontal partition to divide the upper portion, C'', from the lower portion, C''. The chimney D or outlet therefrom being located above the flue C, the heat and products of combustion first pass through the lower portion, C'', then up and over the partition C' and through the upper portion, C'', to the chimney or outlet. Q are doors by which access can be had to the floor of the roasting-chamber.

The chamber B being at right angles to the chamber A, access can be had to the forward end as well as the side of the latter, and the chimney as located is in a central position.

I claim as my invention—

1. The horizontal furnace herein described, comprising smelting-chamber A, having doors P P' at the side and outer end, respectively, and the roasting-chamber B, at right angles to the smelting-chamber, connected to the latter by a flue, C, and having doors, substantially as set forth.

2. The horizontal furnace comprising smelting-chamber A, having doors P P', roasting-chamber B, at right angles thereto and having doors, flue C, connecting the chambers, and a chimney, D, in a central position above the flue, substantially as set forth.

JOHN NEVILLE.

In presence of—

GEO. H. KNIGHT,
SAM'L KNIGHT.
